UNITED STATES PATENT OFFICE.

MELVILLE CLARK, OF CHICAGO, ILLINOIS, ASSIGNOR TO MELVILLE CLARK PIANO COMPANY, OF CHICAGO, ILLINOIS, A CORPORATION OF ILLINOIS.

STOP-RECORDING ACTION FOR AUTOMATIC MUSICAL INSTRUMENTS.

1,082,500.

Specification of Letters Patent.

Patented Dec. 30, 1913.

Application filed September 18, 1911. Serial No. 649,191.

To all whom it may concern:

Be it known that I, MELVILLE CLARK, a citizen of the United States, residing at Chicago, in the county of Cook and State of Illinois, have invented new and useful Improvements in Stop-Recording Actions for Automatic Musical Instruments, of which the following is a specification, reference being had to the accompanying drawings, 10 forming a part thereof.

The purpose of this invention is to provide means for recording the voluntary actions of the operator in manipulating the stops or devices of whatever sort provided 15 in an automatic musical instrument for enabling the operator to modify the playing action.

It consists in the elements and features of construction shown and described as indicated in the claims.

In the drawings:—Figure 1 is a front elevation of a portion of a piano having automatic playing devices provided with this invention. Fig. 2 is a section at the line 25 2—2 on Fig. 1. Fig. 3 is a diagrammatic view illustrating the connection between pneumatically-controlled stop devices and the devices for recording the operation of said stop devices. Fig. 4 is a detail elevation of the primary pneumatic chamber having its wall partly broken away to show the interior.

The drawings show a portion of an upright piano with parts which will be recognized without special mention, having automatic playing mechanism, of which the roll carriage and tracker are shown mounted in a customary position above and back of the manual, 1 being the roll carriage, 2 40 the note sheet, 3 the music roll, 4 the take-up roll, 5 a conventional representation of the roll-actuating mechanism, which may be of any familiar type. Upon the roll carriage, there is mounted a pneumatic action 45 comprising a primary pneumatic chamber, 6, and mounted upon and connected with it in the customary way motor pneumatics, 7, 9, 11 and 13 at one end, and 8, 10, 12 and 14 at the other end, having their moving 50 walls, respectively, positioned so that fingers extended from them may carry pencils, 15, whose points are advanced against the marginal portions of the note sheet by the collapse of the pneumatics respectively. Said 55 motor pneumatics are controlled by corre-

sponding primary pneumatics, 7^a, 9^a, 11^a, 13^a and 8^a, 10^a, 12^a and 14^a, respectively, mounted, as usual, within the primary pneumatic chamber, and having ducts leading to an edge thereof for connection as herein-after described.

At the manual front, there are represented finger keys or push buttons, A, B, C and D, and A¹, B¹, C¹ and D¹, carrying, respectively, valves, a, b, c, d, and a¹, b¹, c¹ and d¹, which control ducts, A², B², C², D², and A³, B³, C³ and D³, which are indicated as leading to pneumatic devices for causing several modifications in playing as follows: A² and A³, to pneumatics for opening and closing, respectively, high-tension bellows throttle valve; B² and B³, to pneumatics for opening and closing, respectively, the low-tension bellows and shut-off valve; C² and C³, to pneumatics, respectively, for adjusting the hammer rest rail inward and outward; D² and D³, to pneumatics, respectively, for depressing and releasing the sustaining pedal. It is not thought necessary to illustrate these various modifying mechanisms, as they may be of any sort comprising operating pneumatics acting for the purposes stated, in any familiar manner. From the primary pneumatics, 7^a, 9^a, 11^a, 13^a, and 8^a, 10^a, 12^a and 14^a, tubes a², b², c², d², and a³, b³, c³ and d³, lead respectively to, and make conjunction with, the tubes, A², B², C² and D², and A³, B³, C³ and D³, anterior to the valves which control said ducts, respectively, so that the opening and closing of said valves simultaneously controls the primary pneumatics to which one set of tubes lead and the tone-modifying devices to which the other set of tubes lead. The result is obviously that when the operator operates any key or stop button for producing any desired modification in the playing, a pencil corresponding to the modifying device thus brought into action is depressed on to the note sheet and produces a longitudinal mark thereon, corresponding in length to the time during which the modifying device involved is kept in action for modifying the playing in accordance with its special function. There is therefore produced upon the margin of the note sheet a series of markings accurately recording the manipulation of all the stops or controlling devices by the operator. These markings serve as a pattern from which, subsequently,

100
105
110

note sheets may be cut for reproducing automatically the same modifications which the operator has produced at will in producing the markings.

5 I claim:—

1. In an automatic musical instrument, in combination with a tracker and a note sheet for traveling thereover to control the playing of the instrument, a pneumatic action comprising motor pneumatics; markers actuated by the motor pneumatics, respectively, mounted at pre-determined positions in the width of the note sheet with capacity for advancing their points against and reTRACTING them from the note sheet at its bearing on the tracker; devices for modifying the playing; manually-operated valves for controlling said modifying devices, and air connections from the pneumatics, respectively, which are controlled by said valves, respectively.
2. In an automatic musical instrument, in combination with pneumatically-operated means for modifying the playing, a tracker and a note sheet mounted for traveling thereover to control the playing; a pneumatic action having a motor pneumatic for each such modifying means; a marker actuated by said motor pneumatic mounted at a pre-determined position in the width of the note sheet for advancing its point against the marginal portion of the note sheet at the bearing of the latter on the tracker; a primary pneumatic which con-

trols such motor pneumatic; a duct from such primary pneumatic, and a duct from the corresponding pneumatically-operated modifying device, and a manually-operable valve which controls both said ducts.

3. In an automatic musical instrument, in combination with a pneumatically-operated device for modifying the playing and pneumatic means for operating such modifying devices; a manually-operated valve which controls said pneumatic; a tracker, and a note sheet mounted for traveling over the tracker and controlling the playing of the instrument; a pneumatic action comprising a motor pneumatic mounted with its moving wall at a pre-determined position opposite the tracker; a marker carried by such moving wall positioned for advancing its point against the note sheet at a pre-determined longitudinal line thereof and at the bearing of the note sheet on the tracker; a primary pneumatic which controls such motor pneumatic, and a duct leading from said primary pneumatic to the manually-operable valve pertaining to said modifying device.

In testimony whereof, I have hereunto set my hand at Chicago, Illinois, this 1st day of September, 1911.

MELVILLE CLARK.
